UNITED STATES PATENT OFFICE.

WILLIAM C. SOLE, OF SULLIVAN, INDIANA.

WELL-DRILLING MACHINE.

1,274,950.

Specification of Letters Patent.

Patented Aug. 6, 1918.

Application filed December 6, 1916. Serial No. 135,308.

To all whom it may concern:

Be it known that I, WILLIAM C. SOLE, a citizen of the United States, and a resident of Sullivan, in the county of Sullivan, and 5 State of Indiana, have invented a new and Improved Well-Drilling Machine, of which the following is a full, clear, and exact description.

My invention has for its object to provide a well drilling machine in which are combined the good qualities of the stationary and of the portable well drilling machines now in use.

My well drilling machine is provided with 10 three sheaves disposed above each other, and three reels, so that the casing line, the drilling cable, and the sand line are permanently installed, the casing line and the sand line being secured at one side when drilling, but 15 being, nevertheless in a position which admits of their almost instant use. The calf reel, the bull reel, and the sand reel are positioned to obtain the greatest power at the calf reel when the casing is to be raised, a spudding pulley being adjustable on the calf reel to engage a spudding cable passing from the bull reel under the calf reel, suitable rocking means being provided for the calf reel during the spudding operation.

Another object of the invention is to provide a friction wheel on the sand reel shaft and a friction wheel on a counter-shaft connected for driving the bull reel shaft, so that either one of the said shafts may be moved to 30 bring its friction wheel into engagement with the friction wheel on the band wheel shaft; or, if desired, into engagement with a brake shoe.

Additional objects of the invention are to 35 provide a clutch, to connect the bull reel shaft with its driving means when desired, and to provide adjustable bearings for the sand reel shaft and the counter-shaft.

Still other objects of the invention will 40 appear in the following specification, in which the preferred form of the invention is disclosed.

In the drawings similar reference characters denote similar parts in all the views, in 45 which—

Figure 1 is a side elevation showing my drilling machine;

Fig. 2 is an enlarged plan view of Fig. 1, but without the mast;

Fig. 3 is a view showing one side of Fig. 55 2, but without the engine and its frame;

Fig. 4 is a sectional view on the line 4—4 of Fig. 2;

Fig. 5 is a view showing the other side of Fig. 2, but without the engine and its frame; 60

Figs. 6, 7 and 8 are fragmentary views showing the forms of the adjustable bearings used for the sand reel shaft and the counter-shaft;

Fig. 9 is an enlarged sectional view on 65 the line 9—9 of Fig. 2;

Fig. 10 is an end view of Fig. 9; and

Fig. 11 is a sectional view on the line 11—11 of Fig. 9.

By referring to the drawings, it will be 70 seen that the well drilling machine has a frame 15 with supporting wheels 16 disposed under the frame, these supporting wheels resting on sills 17 when the machine is to be used, there being a transverse sill 18 which 75 rests on the sills 17, the main mast 19 being mounted on this transverse sill 18. The front wheels 16, which rest on the sills 17, are disposed against the transverse sill 18 and are held in this position by blocks 19^a 80 which are tied to the transverse sill 18 by tie-bolts 20. In a similar manner, blocks 21 are disposed at the front and at the rear of the rear wheels 16, these blocks 21 being tied together by bolts 22. The frame 15 is tied 85 down to the sills 17 by means of rods 23 which are connected by turn-buckles 24. By this means the frame 15 may be moved to the position where it is to be used, on its wheels 16, and may be quickly and conveniently 90 mounted on and secured to the sills 17, in the manner set forth.

The main mast 19 is mounted on the transverse sill 18 on the longitudinal center line 95 of the frame, and this main mast 19 leans forwardly, as shown in Fig. 1 of the drawings, so that the drilling cable 26 as it passes forwardly over the crown sheave 25, will be plumb with the center of the drill hole. Great strength and stability are obtained by 100 this construction. The drilling cable 26 is wound on a bull reel 27 secured for rotating with a bull reel shaft 28. It will be seen by referring to Fig. 2 of the drawings that this bull reel 27 is very wide, extending from 105 side to side of the frame 15. A calf reel 29 is mounted on a calf reel shaft 30 journaled in bearings 31 in the frame 15. This calf

reel 29 is disposed adjacent the main mast 19 in order to obtain the greatest power during casing operations. This calf reel 29 is in a position where it may be watched by the 5 operator when the casing is being raised. A casing line 32 passes from the calf reel 29 over a sheave 33 mounted on the main mast 19 below the sheave 25, the casing line 32 is the fall of a tackle 34 supported on the 10 bracket 40 by a rod 34^a. A line 34^b is secured to the rod 34^a and it passes over a sheave 34^c to a lever 34^d and by operating the lever 34^d the tackle 34 may be moved to one side. Above the crown sheave 25 there is a sand 15 sheave 35 which is carried by the main mast 19, a sand line 36 passing from the sand reel 37 over the sand sheave 35, it being possible to secure the end 38 of this sand line to one of the auxiliary masts 39 when not in use. 20 These auxiliary masts 39 are secured to the main mast 19 by brackets 40.

It will be understood by referring to Fig. 1 of the drawings that the relative positions of the calf reel 29, the bull reel 27, the sand 25 reel 37, and the sheaves 33, 25 and 35, will enable the operator to thread the crown sheave 25 with a heavy drilling cable by pulling it up with the sand line 36, inasmuch as the sand line sheave 35 is above the 30 crown sheave 26. It will also be seen that as the sand line sheave 35 is above the crown sheave 25, it is impossible for water to run from the drilling line to the sand line sheave 35, which, with drilling machines now in 35 use causes great difficulty, as this water freezes in winter. The casing line 32, the drilling cable 26, and the sand line 36 are permanently installed, and it is never necessary to substitute one cable or line for another. 40 This is so, although the cables do not cross each other at any place, which would result in unnecessary wear.

The free ends of the sand line 36 and the casing line 32 hang as near plumb with the 45 center of the hole over which the drilling cable 26 hangs, as is possible when using three separate lines over their respective pulleys. When using my drilling machine, should the casing commence to slip, the casing line 32 may be almost instantly used to 50 raise the casing.

The main mast 19 is raised by the engine, and the auxiliary masts 39 are swung into position from the main mast, and are secured together by means of the bracket 4.

The calf reel 29 is used for spudding, a spudding pulley 41 being mounted on an arm 42 which may be bolted to a flange 43 on the calf reel 29, when desired. When 60 spudding, the spudding cable is secured to the bull reel 27, and passes under the spudding pulley 41, and then up the mast and over the crown sheave 25. The calf reel shaft 30 is given a rocking movement by 65 means of a pitman 44 which connects a wrist

pin 45 on a pulley 46 carried by the band wheel shaft 47, with a wrist pin 48 on a pulley 49 mounted on the calf reel shaft 30. The wrist pin 48 has a greater radius than the wrist pin 45.

During casing operations, the pitman 44 is removed, and a pulley 50 on the band wheel shaft 47 is connected with a pulley 51 on the calf reel shaft 30 by a wire rope 52. This wire rope 52 is given one and one-half 70 turns around each of the pulleys 50 and 51, to prevent any possible slippage. When the casing is very heavy and hard to pull, the wire rope 52 is removed from the pulley 50, and is disposed around the pulley 46, which is secured thereto, the wire rope 52 being also removed from the pulley 51 and being disposed around the pulley 49, which is secured to the pulley 51. While the pulleys 49 and 51 are of the same diameter, the 75 diameter of the pulley 46 is less than the diameter of the pulley 50, so that while the wire rope 52 will be disposed one and one-half times around the pulley 49, it will be disposed two and one-half time around the pulley 46.

The engine 53 is mounted on a frame 54, two pulleys 55 and 56 being secured to the ends of a shaft 57, the pulley 56 being of less diameter than the pulley 55, and the pulleys 50 and 56 being substantially in alinement with pulleys 58 and 59, which are of substantially the same diameter and which are secured to the band wheel shaft 47. Under normal conditions, the pulley 55 is connected with the pulley 58 by a wire rope 60, the wire rope 60 being given one and one-half turns around each of the pulleys 55 and 58. However, when desired, the wire rope 60 may be used to connect the pulleys 56 and 59, the difference in size between the pulleys 55 and 56 permitting the wire rope 60 to be disposed two complete turns around the pulley 56, and one complete turn around the pulley 59. By using this means of changing the speed, the heavy balance weights which it is customary to bolt to the fly wheel of a drilling engine when a certain depth is reached, may be dispensed with. The result is a better balanced and smoother running engine, and allows the speed of the engine to be increased as desired.

By making use of the wire ropes 60 and 52 for connecting the pulleys, and by giving the wire rope 60 at least one complete turn around each of the pulleys, all slippage is done away with, even should the machine be exposed to the weather. It will be understood that the slack of the wire rope 60 is taken up with a jack screw 61, which keeps the engine frame 54 spaced from the frame 15.

The band wheel shaft 47 is journaled in bearings 62 on the frame 15, and secured to this band wheel shaft 47 there is a metal

friction wheel 63. The sand reel shaft 64 on which the sand reel 37 is secured, carries a friction wheel 65 having preferably a wooden face, it being possible to move the sand reel shaft 64 so that the friction wheel 65 may be brought into engagement with the friction wheel 63 on the band wheel shaft 47, or with a brake shoe 66 mounted on the frame 15. The friction wheel 63 not only is adapted to drive the sand reel shaft 64 by means of the friction wheel 65, but the friction wheel 63 is also adapted to engage a friction wheel 67 on a counter-shaft 68, it being possible to move this counter-shaft 68 so that the friction wheel 67 will engage the friction wheel 63 or a brake shoe 69 carried by the frame. The friction wheel 67, as well as the friction wheel 65, is provided with a wooden face. The counter-shaft 68 serves to drive the bull reel 27 by means which I will shortly describe.

At one side of the frame, the sand reel shaft 64 and the counter-shaft 68 are journaled in similar bearings 70, these bearings 70 being shown in Fig. 7 of the drawings. Each of these bearings 70 has a base 71 mounted on the side of the frame, each base having upwardly extending arms 72 with threaded orifices 73 therein, a ring 74 being disposed between the arms 72, and being engaged by set screws 75 which mesh in the threaded orifices 76 in the ring 74, the axes of the threaded orifices 76 being preferably at right angles with the axes of the threaded orifices 73. A bearing member 77 is disposed within the ring 74 and is engaged by set screws 78 which mesh in the threaded orifices 76. The shaft is journaled in this bearing member 77. The counter-shaft 68 is journaled at the other side of the frame in a bearing 79, this bearing 79 being substantially the same as the bearing 70, with the exception that the base 71^a is pivoted to the frame 15 at 80, instead of being secured to the frame 15 by bolts 81, as is the case with the bearing 70. A depending arm 82 extends from the base 71^a so that the bearing may be moved to carry with it an end of the counter-shaft 68, so that the friction wheel 67 thereon may be moved into or out of engagement with the friction wheel 63 and the brake shoe 69. A bearing 84 in which the other side of the sand reel shaft 64 is journaled, is constructed substantially the same as the bearing 79, with the exception that instead of the depending arm 82, the bearing 84 has an upwardly extending arm 85. It will be understood that the bearings 70, 79 and 84, are self-aligning, and they serve to keep the shafts from cutting out the bearing material when the shafts are moved in the manner set forth. The bearing 70 is designed to give considerable adjustment by manipulation of the set screws, while the bearings 79 and 84 are designed principally

to permit the desired movement of the shafts journaled therein.

At the end of the frame 15, adjacent the main mast 19, there are four levers 86, 87, 88 and 89, the lever 87 being connected with 70 the depending arm 82 of the bearing 79 by means of a link 90. The lever 86 is connected with the upwardly extending arm 85 of the bearing 84 by means of a link 91. It will be seen that a forward pull of the 75 lever 87 will move the friction wheel 67 into engagement with the friction wheel 63, and that a forward pull of the lever 86 will move the friction wheel 65 into engagement with the friction wheel 63. The lever 88 is 80 connected with a brake band 92 disposed around a brake drum 93 mounted on the sand reel shaft 30. The lever 89 is connected with a brake band 94 by a link 95, the brake band 94 being disposed around a 85 brake drum 96 mounted on the bull reel shaft 28. With this construction, it will be seen that the operator may stand adjacent the main mast 19 and operate the machine.

As has been stated, the counter-shaft 68 is used for driving the bull reel 27, the bull reel 27 being secured to the bull reel shaft 28, which is journaled in bearings 97 on the frame 15. Rotatably mounted on the shaft 28 there is a sprocket wheel 98 which has two inner transverse key slots 99 disposed opposite each other, which are adapted to register with longitudinally disposed key slots 100 on the shaft 28. Mounted for moving in these key slots 100 there are keys 101 100 which when they are moved inwardly engage the sprocket wheel 98 at its key slots 99. The keys 101 are connected at their outer ends to a transverse member 102 which is adapted to move in a slot 103 in the shaft 105 28. The outer portion of the shaft 28 is reduced in diameter, and around this outer portion there is disposed a spring 104 which is secured at its inner end 105 to the shaft 28, and at its outer end 106 to the transverse member 102, this spring serving to pull the transverse member 102 inwardly, and with it the keys 101, so that the keys will engage the sprocket wheel 98 at its key slots 99, the transverse member 102 passing into the slot 103 in the shaft 28. It will be understood that with this construction the keys 101 will normally engage the sprocket wheel 98 at its key slots 99, but that the keys 101 may be withdrawn therefrom. Pivoted to 110 the transverse member 102 there is an arm 107, which may pass with the transverse member 102 into the slot 103, but which may be rotated relatively to the transverse member 102 when the transverse member 102 is drawn outwardly, so that the arm 107 may engage the outer end of the shaft 28 to hold the transverse member 102 with its keys 101 out of operative position. In Fig. 2 of the drawings, I show a sprocket 115

120 125 130

wheel 108 similarly mounted on the counter-shaft 68, but it will of course be understood that this sprocket wheel 108 may be permanently secured to the counter-shaft 68 if desired. The sprocket wheels 108, and 98, are connected by a sprocket chain 109. It will be understood that the keys 101 may be withdrawn to permit the bull reel shaft 28 to rotate relatively to the sprocket wheel 98 when tools are being lowered into the drill-hole, the brake which has been described being used to regulate the speed of the bull reel shaft 28.

Having thus described my invention, I claim as new and desire to secure by Letters Patent:

1. In a well drilling machine, a frame, a main mast extending upwardly and forwardly from the frame, an auxiliary mast disposed in front of the main mast, a bracket secured to and extending from one mast to the other, a lower sheave, an intermediate sheave, and an upper sheave, the sheaves being journaled in bearings in the main mast, a calf reel journaled in bearings in the frame on a transverse axis and adjacent the main mast, a bull reel journaled in bearings in the frame on a transverse axis and at the rear of the calf reel, a sand reel journaled in bearings in the frame on a transverse axis and in the rear of the bull reel, a tackle secured to the bracket, the fall of the tackle being disposed over the lower sheave

and down to the calf reel, a drilling rope extending from the intermediate sheave down to the bull reel, and a sand rope extending from the upper sheave down to the sand reel.

2. In a well drilling machine, a frame, a main mast extending upwardly and forwardly from the frame, two auxiliary masts disposed in front of the main mast and converging upwardly, brackets connecting the upper portions of the auxiliary masts with the main mast, a lower sheave, an intermediate sheave, and an upper sheave, the sheaves being journaled in bearings in the main mast, a calf reel journaled in bearings in the frame on a transverse axis and adjacent the main mast, a bull reel journaled in bearings in the frame on a transverse axis and at the rear of the calf reel, a sand reel journaled in bearings in the frame on a transverse axis and in the rear of the bull reel, a tackle secured to the bracket, the fall of the tackle being disposed over the lower sheave and down to the calf reel, a drilling rope extending from the intermediate sheave down to the bull reel, a sand rope extending from the upper sheave down to the sand reel, a pulley on one of the auxiliary masts, and a cord secured to the top of the tackle and disposed over the pulley and downwardly.

WILLIAM C. SOLE.
